ATTORNEY

UNITED STATES PATENT OFFICE

JOHN ANDREWS, OF OAKLAND, CALIFORNIA

ROTARY KILN

Application filed May 24, 1928. Serial No. 280,326.

This invention relates to improvements in rotary furnaces for reducing ores, more particularly, in those employed in the treatment of mercury bearing ores, such as cinnabar. The furnaces generally employed for this purpose are constructed on a large scale and are permanently installed for long continuous operation. For the profitable installation and operation of such a permanent furnace, it is necessary to have readily available a large supply of ore for the long continued operation of the furnace. In some localities cinnabar is found deposited in small pockets and widely distributed over territory where transportation is difficult. In such a locality, the installation of a permanent furnace would be impractical, for the closely adjacent ore would soon be exhausted and the difficulty in the transportation of the more remote ore would render the project unprofitable. Also, the transportation of the massive structural units of which the permanent furnace is ordinarily constructed would be impractical.

One of the objects of the instant invention is the provision of a rotary furnace of a knock-down character, so constructed in units that it can be readily transported over rough country, easily assembled in operative relation, and also readily dismounted for transportation to a different locality for installation there. By employing such a furnace, widely distributed ores in small quantities can be treated on a remunerative basis. It also has for its object certain improvements in the details of construction to render the furnace efficient in its purpose, to which particular reference is made further on.

The invention consists in the novel construction, combination and arrangement of parts hereinafter described, pointed out in the appended claim and illustrated by the accompanying drawings.

In the accompanying drawings, in which similar reference characters designate corresponding parts,

Figure 1 is a longitudinal sectional view of a rotary furnace embodying the invention.

Figure 2 is a detail perspective view, showing a part of the feed-bar.

Figure 3 is a plan view of the furnace.

Figure 4 is a detail view of the feed chute, being a perspective sectional view on the line 4-4 of Fig. 1.

Figure 5 is a detail perspective view, showing a part of the feed bar for moving the material in the feed spout.

Referring to the drawings in detail 5 designates the cylindrical furnace formed of short tubular sections 6 having flanges 7 at their ends in abutting relation and secured together by bolts. To facilitate the assembling of the sections, the contacting faces of their flanged ends are machined to provide flat contacting faces normal to the longitudinal axis of the sections. This uniformity in the ends of the sections permits them to be brought together without requiring particular selection or fitting and a tight joint is assured. Should there be irregularity in the end faces of the sections, a gasket 8 can be interposed to provide a tight joint. While the cylindrical furnace is shown as being composed of three sections, it is to be understood that the number of sections may be varied to meet different requirements. The tubular sections are quite short, as compared with those employed in a permanent plant, so that the weight of a section is not too great to be readily transported.

The furnace is mounted so as to be slightly declined toward its delivery end so that the material being treated will tend to travel by gravity through the retort. It is mounted for rotation on the rolls 9 bearing against the peripheries of the joined flanges, these peripheries being also machined to provide a smooth bearing for the rolls. The rolls 9 are journaled on bearings carried by the pillars 10 mounted on suitable foundations. On an end of one of the tubular sections is mounted the bevel gear 11 adjacent the flange thereof, the bolts passing through the adjacent flanges also extending through the gear to hold the latter in place. With the gear 11 meshes the bevel gear 12 on an end of the shaft 13 journaled in bearings suitably mounted on the pillar block 14. On the other

end of the shaft 13 is the gear 15 meshing with the pinion 16 on the shaft 17 journaled in bearings on the pillar block. This shaft 17 carries a pulley 18 driven by a belt 19 leading from a motor 20. On the shaft 21 journaled on the pillar block is the roll 22 engaging the bevel gear 11 opposite to the gear 12, the roll operating to hold the two gears 11 and 12 in mesh.

On the inner face of the furnace is a shallow spiral flange 23 and the direction of rotation of the furnace is such that the flange acts as a worm that tends to move the material toward the discharge end of the furnace. Also, as the retort rotates the spiral flange cascades the material in the furnace. That is, the flange on the ascending side of the furnace lifts the material from the lower side and as the flange travels upward the material is gradually dropped and showers across the interior of the furnace. This treatment of the material separates the particles so that they are individually exposed to the action of the gases flowing through the furnace.

At the lower or discharge end of the furnace is a low pressure burner 24 for fluid hydrocarbon, positioned to direct the flame into the furnace and toward the cascading ore which serves as insulation means and protection for the wall of the retort. From this it will readily be seen that the maximum of efficiency of the fuel consumed will be obtained. The burner is mounted through a sheet steel housing 26—A, which extends from the end of the housing 26, hereinafter referred to, to the tip of the discharge pit. Surrounding and enclosing discharge end of the furnace is provided the continuous housing 26 and 26—A to retain the heat imparted to the lower end of the furnace by the burner 24.

At its upper or material receiving end the furnace opens into the dust chamber 27, which is of large volumetric capacity and is provided with communicative means to deliver the vapor to the usual series of condensers, after the dust has been precipitated to the bottom of the dust chamber. Mounted directly behind the dust chamber and in direct line with the furnace is the hopper 28 and feeding device to receive the material to be treated. Leading from the lower end of the hopper, through the dust chamber, is the tube 29 emptying into the upper end of the retort. Between the hopper 28 and the end of the tube 29, is provided the spout 58, open on its upper side to permit ready inspection should congestion occur in the tube 29. Reciprocatively through the tube and spout is the feed bar 30, rectangular in cross-area and with its corners notched, as at 31, to provide edges to engage the material to move the latter along the spout and tube as the bar is reciprocated therein. The feed

bar is mounted in the guide rods 32 (Fig. 4) extending across the spout and the ends of said guide rods run free under guide plates 59 provided on both sides of the spout 58, for the purpose of preventing the feed bar 30 from rising to the top of the feed tube 29, and to permit an even movement of the material through the spout and tube. The upper end of the feed bar is hinged to one end of the walking beam 33 pivoted to the bracket 34. The other end of the walking beam is connected by the rod 35 with the gear 15 so that rotation of the latter, through the intervening mechanism, imparts a reciprocative movement to the feed bar 30.

While this method of feeding is constant and will deliver a sufficient amount of ore into the furnace at all times, there is no positive amount delivered in one given stroke, thereby avoiding all danger of jamming and breakage. The conduit formed by the spout 58 and the tube 29 is of considerable cross-area and is of large carrying capacity. The conduit is slightly declined from the horizontal so that the movement of the material therein is slow, as effected by gravity. Also, the forward movement of the material in the conduit is but slightly augmented by the reciprocation of the notched feed-bar 30, which acts more to prevent the material from packing than to accelerate the movement. As a result of this slow movement of the material, the conduit remains filled and the opening through the conduit to the exterior of the dust chamber is sealed so that gases cannot escape therethrough. While the movement of material in the conduit is slow, yet the large bulk of the material so moved insures that the required amount be fed to the retort.

The operation of the apparatus is as follows: The parts having been assembled at a locality with a supply of ore at hand and the furnace erected, the fuel at the burner 24 is ignited to project the flame into the lower or discharge end of the rotary furnace 5. The products of combustion entering the retort pass through the same to the dust chamber 27. This causes a strong draft through the furnace and the air entering the lower end of the same is heated as it passes over the flame projected into the furnace by the burner.

The products of combustion, passing from the rotary furnace 5 into dust chamber 27, heat the latter to a high degree of temperature. The high temperature in the dust chamber preheats the material being treated as it passes through the tube 29. Owing to the large volumetric capacity of the dust chamber, the cold material entering through the conduit will have but little chilling effect on the products of combustion in the dust chamber and the high temperature will be maintained therein. Although there is

considerable bulk in the material passing through the conduit, yet the extensive heat-exchange surface of the conduit and the slow travel of the material therethrough insure a thorough preheating of the material before it passes into the rotary furnace.

The material to be treated is fed into the hopper 28 by any suitable means (not shown). The motor having been started, the feed bar 30 reciprocating in the spout 58 and the tube 29, forces the material downward through the tube to be fed gradually into the upper end of the rotating furnace 5. The tube 29 has considerable length so that the material filling the same closes the passage therethrough so that the heated gases from the furnace cannot escape through the tube. The heated gases entering the dust chamber and heating the interior thereof, also imparts a preliminary heating to the material as it travels through the tube. The material entering the upper end of the rotating furnace tends to gravitate to the lower end of same. Also, the spiral flange or worm 23 tends to 25 propel the material toward the lower end of the furnace, the latter being rotated in the direction required for the purpose. As the furnace rotates the flange on the upward moving side of same picks up the material and cascades it across the interior of the furnace. In this way the material is so agitated and distributed that the individual particles are exposed on all sides to the reducing action of the heated gases flowing through the furnace.

During the reducing operation, the interior of the furnace, particularly the lower part thereof, is maintained at a temperature considerably above that at which cinnabar decomposes and mercury vaporizes. Subjected to this temperature in passing through the furnace, the ore is completely disintegrated and the mercury being volatilized, the draft through the furnace carries the gases into the dust chamber 27, where the dust is precipitated and removed to the bottom of the chamber. The mercurial vapor is conducted from the dust chamber through the exit pipe 57 to the condensing system.

50 The spent ore discharges from the lower end of the furnace into the pit 25. In its passage through the furnace the ore collects along the lower side thereof. At the discharge end of the furnace the burner directs the flame against the ore bed collected in the lower side of the furnace to protect the wall to some extent against the direct action of the flame and also to subject the remaining refractory ore to the highest temperature of the furnace.

What I claim is:

In an apparatus for treating ores, the combination of a cylindrical furnace, means for rotating the furnace, said furnace having a spiral flange on its inner face to form a worm

for feeding the material being treated through the furnace as the latter is rotated, said flange also operating to cascade the material within the furnace, means for introducing heated gases into the delivery end of the furnace, a dust chamber of large volumetric capacity communicating with the material receiving end of the furnace, a feed spout and tube of large cross-area extending through the dust chamber to empty into the material receiving end of the furnace, said conduit having extensive heat-exchange surface within the dust chamber and means for slowly propelling the material through the feed spout and tube, the slow movement of the material through the feed spout and tube tending to fill the same to close the opening therethrough to the exterior of the dust chamber, and said slow movement of the material and the extensive heat-exchange surface of the conduit operating to preheat the material within the dust chamber before the material is discharged into the cylindrical furnace.
